WALKING BEAM ADJUSTER

Robert W. Bier, Dallas, Tex.

Application October 4, 1934, Serial No. 746,825

14 Claims. (Cl. 255—17)

This invention relates to new and useful improvements in walking beam adjusters.

One object of the invention is to provide improved means for longitudinally adjusting a walking beam to properly position it with relation to a polish rod or reciprocating element connected to the end of the beam.

A particular object of the invention is to provide means for hydraulically adjusting a walking beam with relation to the perpendicular path of travel of the reciprocating element connected to the beam, whereby a more minute or finer adjustment may be made, and the beam more accurately positioned and controlled during such adjustments.

Another object of the invention is to provide means constituting a guide, while the beam is being adjusted, and arranged to positively clamp and hold the beam in its adjusted positions.

A further object of the invention is to provide a mounting for a walking beam of a well pumping rig, having means for retracting said beam from over the well to permit the running or pulling of tools, tubing, or casing; or work of any nature that will require a free space above the well.

Still another object of the invention is to provide a longitudinally adjustable walking beam so arranged that either end may be abnormally projected to lengthen or shorten the swinging stroke of said beam which may be necessary under certain conditions, such as the taking of potentials or the like.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view of a device constructed in accordance with the invention, partly in elevation and partly in section,

Figure 2 is a transverse vertical sectional view taken on the line 2—2 of Figure 1,

Figure 3 is a similar view taken on the line 2—2 of Figure 1,

Figure 4 is an isometrical view of the beam and its clamping members,

Figure 5 is a detailed view of the valve and pump,

Figure 6 is a vertical sectional view taken on the line 6—6 of Figure 5, showing the rotor of the valve in one position, and

Figure 7 is a similar view showing the rotor in the other position.

In the drawings the numeral 10 designates the usual Samson post or other support. A bearing saddle 11 is mounted on the upper end of the post. An elongated cradle 12 is provided with a transverse rocker 13 which engages in the saddle. This rocker is lubricated by an oil bath 14 in the upper portion of the saddle. The cradle has an arcuate dust hood 15 overhanging the upper end of the saddle. It is pointed out that the cradle may be pivoted on the Samson post in any suitable manner. Caps 16 are bolted on the saddle and overhang the dust hood 15 to prevent dirt and other extraneous matter entering the oil bath 15 and also, to form end plates for the bath.

The cradle is provided at its central portion with a transverse boss 17. A walking beam 18 is slidably supported by the boss and is preferably of the I-beam type. The cradle includes arms 19 which extend longitudinally from each side of the boss 17. Upwardly inclined brackets 20 are formed at the outer end of each arm on each side of the cradle. These brackets are provided with clamps 21 at their upper ends for engaging the longitudinal edge portions of the base flange 18' of the walking beam 18.

Attention is called to Figure 4, wherein it is pointed out that the walking beam is slidably supported in the clamps, as well as upon the boss. 30 The clamps are recessed, so that the base flange 18' is confined against lateral displacement. Keepers 22 bolted on top of the clamps overhang and engage the base flange to fasten the beam in the cradle. It is pointed out that, when the keepers are loosened, a guide is formed and the beam may be slid longitudinally of the cradle. When the keepers are tightened, the beam is securely fastened to the cradle and will be held in its adjusted position.

An elongated cylinder 23 is disposed longitudinally under the beam and extends through a recess 24 in the boss. The ends of the cylinder are rigidly fastened in boxes 25 carried by the ends of the arms 19 between the brackets 20. The cylinder is thus rigidly attached to the cradle. A plunger rod 26 extends axially through the cylinder and stuffing boxes 27 in the ends of the cylinder. A plunger 28 is fastened on the rod within the cylinder so that, when the plunger is displaced longitudinally of the cylinder, the rod will be likewise displaced.

The ends of the rod 26 are loosely inserted in recesses 29' located in the inner end of each hanger 29. Each end of the rod is screw-threaded 55

and is provided with jamb nuts 30. These nuts are provided to take up any slack or play that may develop between the rod and the hangers. These hangers are fastened to the underside of the base flange 18' and have stop fingers 31 directed toward the cradle and in the path of the arms 19. These hangers may be positioned at any desired points on the beam and are sufficiently spaced apart to permit the plunger 28 to travel any predetermined distance within the length of the cylinder. It is obvious that movement of the plunger in the cylinder will contribute longitudinal movement to the beams.

A hand pump 32 is mounted on an extension 15 33 of the boss at one side of the beam, so as to be out of the path of said beam. Any suitable pump may be used and it may be located in any convenient place either on or adjacent the boss. The pump is provided with an operating lever 47 20 having a plunger 48, depending therefrom. The lower end of the plunger reciprocates in the barrel of the pump and is connected to a piston 49. A suitable packing 50 surrounds the plunger at the top of the barrel for preventing fluid leaking 25 out of said barrel by the plunger. An ordinary four way controlling valve 34 is connected to the pump and preferably mounted thereon, as is shown in Figures 1, 2, 3 and 5. The valve is provided with the usual rotor 35 having cut out portions 36. Inlet duct 37 and outlet duct 38 are 30 diametrically opposite each other in the valve and are connected to the pump. Ports 39 and 40 are positioned diametrically opposite each other and open into nipples 41 and 42.

The ends of the cylinder are connected to the valve by pipes 43 and 44 extending therefrom and engaging in the nipples 41 and 42 respectively. The valve is equipped with an operating handle 45 having a pointer thereon, and an indicating dial 46 for showing in which direction the fluid may flow, when it is pumped. Thus, it will be seen that by turning the rotor 35 the flow of the fluid is controlled, so that the fluid may either be pumped from one end of the cylinder to the other, and vice versa, or it is prevented from flowing at all by the rotor closing the ports 39 and 40.

It will be seen that by operating the valve rotor, the beam may be adjusted in either direction or stopped by closing the ports 39 and 40. Thus, by 50 working the valve rotor back and forth, finer and more minute adjustments of the beam may be obtained.

The operation is as follows: When it is desired to longitudinally adjust the walking beam, the 55 keepers 22 are loosened and the valve operating handle 45 is turned to the proper position. The lever 47 is swung and the fluid is pumped, according to the way the rotor 35 has been set, from one end of the cylinder to the other. The fluid is 60 pumped between the plunger 28 and the end of the cylinder 23 and forces the plunger toward the other end. The beam 18, being connected to the plunger by the plunger rod 26 and the hangers 29, will move longitudinally whenever the plunger 65 is moved.

When it is required to move the walking beam to the right, (Figure 1) the valve is adjusted so that the rotor is in the position shown, in Figure 7. The pipe 43 and port 39 will be connected to 70 the outlet duct 38 and the pipe 44 and port 40 will be connected to the inlet duct 37. The pump is now operated and the fluid is drawn from the right-hand end of the cylinder through the pipe 44 and port 40 and into the pump through the 75 inlet duct 37. The fluid is expelled from the pump

through the outlet duct 38, then through the port 39 and pipe 43, into the left-hand end of the cylinder. The fluid will force the plunger to the right and also, the beam which is connected to the plunger. Thus, it will be seen that the beam can be moved as far to the right as is necessary. The keepers are now tightened and the beam will be clamped in its shifted position.

To limit travel of the beam 18 and the plunger 28, the stop fingers 31 on the hangers 29 engage 10 the ends of the arms 19 of the cradle 12 and thus, the plunger is prevented from becoming jammed in the ends of the cylinder.

When it is desired to move the beam to the left, the rotor is rotated to the position shown, in 15 Figure 6. In this position, the pipe 43 is connected to the inlet duct 37 and the pipe 44 is connected to the outlet duct 38. The rest of the operation is the same. The plunger and beam are now moved to the left and the beam may be 20 fastened by the keepers 22. It is pointed out that, when the rotor covers the ports 39 and 40, the fluid will not be able to travel in either direction and the plunger and beam will be held substantially stationary.

What I claim and desire to secure by Letters Patent is:

1. In a walking beam adjusting device, a support, a walking beam pivotally mounted on said support, and means for hydraulically adjusting 30 said beam longitudinally.

2. In a walking beam adjusting device, a support, a walking beam pivotally mounted on said support, means for hydraulically adjusting said beam longitudinally, and means for fastening the 35 beam in its adjusted positions.

3. A walking beam adjusting device comprising, a support, a cradle pivotally mounted on the support, a beam longitudinally adjustable on the cradle, and hydraulic means for shifting said beam longitudinally with relation to the cradle.

4. A walking beam adjusting device comprising, a support, a cradle pivotally mounted on said support, a beam longitudinally adjustable on said support, means for clamping the beam to the 45 cradle, and a hydraulic actuator carried by the cradle and having a plunger connected with the beam.

5. A walking beam adjusting device comprising, a support, a cradle pivotally mounted on said support, a beam longitudinally adjustable on said support, a hydraulic actuator carried by the cradle and having a plunger connected with the beam, and means for limiting the longitudinal movement of the beam.

6. A walking beam adjusting device comprising, a support, a cradle pivotally mounted on said support, a beam longitudinally adjustable on said cradle, a cylinder carried by the cradle, a plunger in the cylinder and connected to the beam, and means for hydraulically actuating the plunger to move said beam.

7. A walking beam adjusting device comprising, a support, a cradle pivotally mounted on said support, a beam longitudinally adjustable on the cradle, hydraulic means for shifting said beam longitudinally with relation to the cradle, and means for fastening the beam in its adjusted positions.

8. A walking beam adjusting device comprising, a support, a cradle pivotally mounted on the support, a beam longitudinally adjustable on said cradle, means for clamping the beam to the cradle, a hydraulic actuator carried by the cradle and having a plunger connected with the beam,

and means for limiting the longitudinal movement of said beam.

9. A walking beam adjusting device comprising, a support, a cradle pivotally mounted on said support, a beam longitudinally adjustable on said cradle, means for clamping the beam in its adjusted positions, a cylinder carried by the cradle, a plunger in the cylinder and connected to the beam, and means for hydraulically operating the plunger.

10. A walking beam adjusting device comprising, a support, a cradle pivotally mounted on said support, a beam longitudinally adjustable on said cradle, a cylinder carried by the cradle, a plunger in the cylinder and connected to the beam, a pump for flowing a fluid into the cylinder to move the plunger to longitudinally adjust the beam on the cradle, and a valve for controlling the flow of said fluid.

11. A walking beam adjusting device comprising, a support, a cradle pivotally mounted on said support, a beam longitudinally adjustable on said cradle, means for clamping said beam in its adjusted positions, a cylinder carried by the cradle, a plunger in the cylinder and connected to the beam, a pump for flowing a fluid into the cylinder to move the plunger to longitudinally adjust the beam on the cradle, and a valve for controlling the flow of said fluid.

30 12. A walking beam adjusting device comprising,

ing, a support, a cradle pivotally mounted on said support, a beam longitudinally adjustable on the cradle, hydraulic means for shifting said beam longitudinally with relation to the cradle, means for limiting the longitudinal movement of the beam, and means for fastening the beam in its adjusted positions.

5

13. A walking beam adjusting device comprising, a support, a cradle pivotally mounted on said support, a beam longitudinally adjustable on said cradle, a cylinder carried by the cradle, a plunger in the cylinder and connected to the beam, a pump for flowing a fluid into the cylinder to move the plunger to longitudinally adjust the beam on the cradle, a valve for controlling the flow of 15 said fluid, and means for limiting the longitudinal movement of the beam.

10

14. A walking beam adjusting device comprising, a support, a cradle pivotally mounted on said support, a beam longitudinally adjustable on said cradle, means for clamping said beam in its adjusted position, a cylinder carried by the cradle, a plunger in the cylinder and connected to the beam, a pump for flowing a fluid into the cylinder to move the plunger to longitudinally adjust 25 the beam on the cradle, a valve for controlling the flow of said fluid, and means for limiting the longitudinal movement of the beam.
